UNITED STATES PATENT OFFICE.

ARTHUR H. GIBSON, OF EASTON, PENNSYLVANIA, ASSIGNOR TO INGERSOLL-RAND COMPANY, OF NEW YORK, N. Y., A CORPORATION OF NEW JERSEY.

MINING-MACHINE.

1,082,319.

Specification of Letters Patent. Patented Dec. 23, 1913.

Application filed January 15, 1910. Serial No. 538,266.

To all whom it may concern:

Be it known that I, ARTHUR H. GIBSON, a subject of the Crown of Great Britain, and resident of Easton, in the county of Northampton and State of Pennsylvania, have invented new and useful improvements in Mining-Machines, of which the following is a specification.

My invention relates to improvements in mining machines and is directed to machines which are well adapted for use in operating upon coal.

My invention relates more particularly to improvements in coal cutting and loading machines and contemplates the provision of a truck on which is mounted a coal puncher and a conveyer which extends beneath the puncher to a point adjacent to the coal face for conveying the coal broken down by the puncher, back to a point to the rear of the puncher and there deliver it into a coal car for removal to any desired point; the coal puncher truck being movable back and forth over the conveyer.

My invention relates further to improvements in the construction, form and arrangement of the several parts whereby the coal puncher truck may be moved back and forth along the track, by power, and in which the puncher itself may be swung horizontally into different positions by power, and held yieldingly in such positions, and in which the puncher itself may be swung vertically into different positions and held yieldingly in such positions.

A practical embodiment of this invention is represented in the accompanying drawings, in which—

Figure 1 represents the coal mining machine in side elevation in position for use, the front portion of the endless conveyer being shown therein, Fig. 1^a is a continuation of Fig. 1, showing the rear portion of the conveyer and the car for removing the coal, Fig. 2 is a plan view of the part shown in Fig. 1, Fig. 2^a is a plan view of the part shown in Fig. 1^a, Fig. 3 is a detail longitudinal vertical section through the coal mining machine and the front portion of the conveyer, Fig. 4 is a detail longitudinal vertical section through the rear portion of the conveyer and through the coal car, Fig. 5 is a transverse vertical section taken in the plane of the line A—A of Fig. 3, looking in the direction of the arrows, Fig. 6 is a detail

side view on an enlarged scale showing the rear portion of the conveyer, certain of the parts being broken away to more clearly illustrate the parts back of the same, Fig. 7 is an enlarged detail plan view of one of the coal carrying bars and one of the side chains of the conveyer, Fig. 8 is a detail section through the same in the plan of the line B of Fig. 7 looking in the direction of the arrows, Fig. 9 is a detail longitudinal vertical section on an enlarged scale of the front end of the conveyer, Fig. 10 is a transverse section taken in the plane of the line C—C of Fig. 9, looking in the direction of the arrows, Fig. 11 is an enlarged transverse vertical section taken in the plane of the line D—D of Fig. 1, looking in the direction of the arrows, Fig. 12 is a detail horizontal section taken in the plane of the line E—E of Fig. 11, looking in the direction of the arrows, illustrating the yielding worm gear mechanism for swinging the puncher horizontally, Fig. 13 is a detail view showing the yielding worm gear mechanism for swinging the puncher vertically, and Fig. 14 is a detail section taken in the plane of the line F—F of Fig. 13, looking in the direction of the arrows.

The track for the coal mining machine is formed in short sections comprising the bottom plate 1 of sheet metal and the usual track rails 2, 2. These track sections may be connected by tie plates 3 and bolts 4 engaging the abutting ends of the track rails 2, 2, for forming a continuous track.

The coal mining machine is adapted for movement along the track, the body or platform of the said machine being denoted by 5, its front wheeled truck by 6 and its rear traction wheels by 7, 7. The machine is moved along the track by providing a winch 9 around which is wound a rope or cable 10, the ends of which rope or cable being provided with hooks 11, 11, for engaging holes 12, 12, in one of the track rails 2, 2, at points 100 to the front and rear of the winch, so that the machine is moved to the front or rear, according to the direction in which the winch is turned. This winch may be turned either by hand or by power, as desired.

The winch is provided with a large gear 13 which meshes with a small gear 14 on a cross shaft 15 provided with a hand wheel 16. This cross shaft 15 is further provided with a chain and sprocket connection 17, 110

with a cross shaft 18, which cross shaft is provided with a chain and sprocket connection 19 with the shaft of a suitable motor 20 mounted on the platform 5 of the mining machine. This motor 20 may be driven from any suitable source of power, as, for instance, by compressed air or steam, through a main supply pipe 21 and a branch pipe 22.

The coal puncher cylinder is denoted by 23 and the pick by 24. The pick is operated in the usual manner by compressed air or steam fed to the cylinder 23 from the main motive fluid supply pipe 21 through the branch pipe 25.

15 The coal puncher may be swung laterally into different desired angular positions and held yieldingly in such positions by the following mechanism:—A worm gear 26 of ring form is frictionally held between the cylinder support 27 and a ring 28, in the present instance by providing a plurality of bolts 29 projecting from the ring 28 through the base of the support 27 and interposing springs 30 between the base of the said support 27 and the heads 31 of the said bolts 29. A ring 32 is secured to the body or platform 5 by screw bolts 33, the inner edge of which ring overlaps the base of the support 27 for retaining the support in its position.

30 A worm 34 is slidably mounted on a horizontal shaft 35 and meshes with the worm gear 26. This worm is yieldingly held in its normal position by springs 36, 37, interposed between the worm 34 and the thrust bearings 38, 39. The worm 34, shaft 35, springs 36, 37, and thrust bearings 38, 39, are housed within a recess 40 in the platform 5 of the machine. The shaft 35 is driven from a suitable motor 41 mounted on the platform 5, through the following connections:—The shaft of the motor 41 is provided with a pinion 42, which meshes with a gear 43 on a stud shaft 44 mounted on the platform 5. This shaft 44 has a sprocket and chain connection 45 with the shaft 35. The motor 41 is driven by compressed air or steam fed through the branch pipe 46 from the main motive fluid supply pipe 21.

50 The puncher may be swung vertically into any desired angular position and held yieldingly in such position, by the following mechanism:—A worm gear 47 of ring form is frictionally held between one of the trunnions 48 and an outer ring 49, in the present instance by providing a plurality of bolts 50 projecting from the trunnion 48 through the ring 49 and interposing springs 51 between the outer face of the ring 49 and the heads 52 of the said bolts 51. The trunnion 48 and the ring 49 with the frictionally clamped worm gear 47 are rotatably mounted in the side frame 53 of the cylinder support 27 and the other trunnion 54 is rotatably mounted in the side frame 55 of the support 27. A ring 56 is secured by screw

bolts 57 to the side frame 53 with its inner edge overlapping the ring 49 thus serving as a keeper for retaining the trunnions in their position in the side frames of the support 27. A worm 58 is slidably mounted upon a vertical shaft 59, which worm meshes with the worm gear 47. This worm 58 is yieldingly held in its normal position on the said shaft 59 by springs 60, 61, interposed between the said worm 58 and upper and lower ball thrust bearings 62, 63, respectively. The worm 58, shaft 59, springs 60, 61, and ball thrust bearings 62, 63 are located in a recess 64 in the side frame 53. The shaft 59 is rotated by a hand wheel 65 through intermeshing pinions 66, 67.

70 A conveyer is provided for conveying the coal broken down by the pick, which conveyer is supported intermediate its ends upon a frame 68 provided with traction wheels 69, 69, intermediate its ends, which traction wheels are fitted to travel along the track rails 2, 2. The conveyer trough comprises a horizontal portion 70 arranged to extend along the track sections between the track rails 2, 2, and an upwardly and rearwardly extended portion 71 for permitting a coal car 72 to be brought into position beneath the rear end of the conveyer for receiving the coal therefrom and transporting it to any desired point.

75 The platform 5 of the mining machine is so arranged that the mining machine may be moved back and forth over the horizontal portion of the conveyer and partially over the upwardly and rearwardly extended portion thereof.

80 For the purpose of moving the conveyer back and forth from the coal face, the front portion of the conveyer may be lifted away from the track sections and suspended in such position by providing chains 73 depending from the front end of the mining machine platform 5, said chains being provided with hooks for engaging any one of a series of holes 74 along the sides of the horizontal portion 70 of the conveyer trough.

85 The conveyer proper comprises side sprocket chains 75, 75, and cross bars 76 connecting the side chains at intervals. These side chains pass over idler sprocket wheels 77, 77, mounted on a cross shaft 78 at the extreme front end of the conveyer trough. These chains 75, 75, also pass around drive sprockets 79, 79, fixed to a cross shaft 80 at the rear end of the conveyer trough. These sprockets 79, 79, are driven by a motor 81 of suitable form, in the present instance through a pinion 82 on the motor shaft which meshes with a gear 83 on a cross shaft 84, which cross shaft has a sprocket and chain connection 85 with the shaft 80 of the conveyer chain sprockets 79, 79. The motor 81 is operated by motive 90

fluid from the main motive fluid supply pipe 21 through the branch pipe 86. The conveyer chains 75, 75, and their cross bars 76, travel rearwardly from the front to the rear 5 of the conveyer along the bottom of the conveyer trough and travel forwardly between the bottom of the conveyer trough and a false bottom 87. This arrangement keeps the chains and cross bars out of contact with 10 the track sections.

A curved guard 88 is provided for the front end of the conveyer trough to protect the parts immediately back of the guard.

The endless conveyer shown herein has a 15 series of specially formed cross bars for connecting the chains at frequent intervals, each of which cross bars is angular in cross section, in the present instance square, and is provided at each end with a round pivot 20 extension 89, which passes through the overlapping ends of two adjacent chain links and is held in position by a fastening means exterior to the links, said fastening means, in the present instance, being a cotter pin 25 90. The cross bar is held from turning by providing the same with a recess 91 into which a lug 92 on the chain link enters.

From the above description it will be seen that in operation the endless conveyer may 30 be advanced to bring its forward end into close proximity to the coal face. This may be accomplished by attaching the conveyer to the mining machine itself and starting the motor 20 for moving the mining machine 35 and conveyer up into position, the chains 73 being first attached to the front portion of the conveyer trough for lifting the front portion of the conveyer, a short distance from the track sections. The chain 40 73 may then be disconnected to permit the conveyer to rest upon the track sections. The motor 20 may then be operated for moving the mining machine back and forth over the conveyer without disturbing the same. 45 The motor 81 may be used for operating the endless conveyer to bring the coal from the coal face back under the mining machine and from thence upwardly where it will be automatically deposited into the coal car for 50 removal. The motor 41 may be used for swinging the pick back and forth laterally. The vertical movement of the pick may be accomplished by manual control. When it is desired to lay a new track section, the 55 conveyer may be again attached to the mining machine and the motor 20 operated to move the mining machine and conveyer back a sufficient distance to permit the laying of the new track section. By bringing the 60 front end of the endless conveyer close up to

the coal face, it will be seen that a great deal of the coal that is broken down by the puncher will fall directly onto the conveyer, thus requiring less manual labor than heretofore for removing the loose coal from the 65 coal face.

It is evident that various changes might be resorted to in the construction, form and arrangement of the several parts without departing from the spirit and scope of my invention; hence I do not wish to limit myself 70 strictly to the construction herein set forth, but

What I claim is:—

1. A track, a mining machine including a 75 platform, a puncher mounted thereon, a motor mounted on the platform for moving the mining machine back and forth along the track, an endless conveyer, means for removably attaching the conveyer to the mining 80 machine, a motor mounted on the endless conveyer for driving it and a common fluid pressure supply pipe carried by the platform for supplying power to the puncher and motors. 85

2. A track, a mining machine including a platform, a puncher mounted thereon, a motor for driving the mining machine back and forth along the track, a motor for swinging the puncher laterally into different 90 positions, an endless conveyer, means for removably attaching the conveyer to the mining machine, a motor mounted on the endless conveyer for driving it and a common fluid pressure supply pipe carried by 95 the platform for supplying power to the puncher and motors.

3. A track, a mining machine including a platform, a puncher mounted thereon, a motor for driving the mining machine back 100 and forth along the track, a motor for swinging the puncher laterally into different positions, manually operated means for swinging the puncher vertically into different 105 positions, an endless conveyer, means for removably attaching the conveyer to the mining machine, a motor on the conveyer for driving it and a common fluid pressure supply pipe carried by said platform for supplying power to said puncher and 110 motors.

In testimony, that I claim the foregoing as my invention, I have signed my name in presence of two witnesses, this 12th day of January 1910.

ARTHUR H. GIBSON.
